UNITED STATES PATENT OFFICE.

MAURICE R. HORRELL, OF CHANUTE, KANSAS, ASSIGNOR OF TWO-THIRDS TO THE
WESTERN DRILLING TOOL & SUPPLY CO., OF CHANUTE, KANSAS.

OPERATING MEMBER.

Application filed September 14, 1925. Serial No. 56,298.

To all whom it may concern:

Be it known that I, MAURICE R. HORRELL, a citizen of the United States, residing at Chanute, in the county of Neosho and State 5 of Kansas, have invented a new and useful Operating Member, of which the following is a specification.

This invention aims to provide novel means for holding an operating rod or member in adjusted longitudinal positions, the 10 device being of peculiar utility in connection with the clutch-operating rods of a well drilling machine, although the device is capable of general application.

15 In the drawing:—Figure 1 is an elevation, Figure 2 is a plan, Figure 3 is a section about on the line 3—3 of Figure 1, the operating member having been operated through an arc of about 90°, Figure 4 is a 20 section on the line 4—4 of Figure 3, the tooth, however, being in the position of Figure 1, Figure 5 is a section on the line 5—5 of Figure 3, the rod being omitted, and Figure 6 is an elevation showing a slight 25 modification.

The numeral 1 marks a support or standard which may have a transverse foot 2 at its lower end, if the support is to be secured at 3 to the upper surface of a part 4; but 30 if the support is to be fastened to the side of an object, the support 5 (Figure 6) may have a transverse shoulder 6 and a reduced lower end 7.

At its upper end, the support 1 is provided with a laterally extended head 8 wherein an opening 9 is formed, the opening having a reduced upward extension 10. The inner edge of the head 8 has downwardly converging surfaces 11, and in the 40 sides of the head, below the surfaces 11 there are seats 12 which taper inwardly.

An operating member or rod 14 is mounted for longitudinal sliding movement, and for rotation, in the opening 9 of the head 8, 45 and carries a handle 15. The operating rod 14 is provided with outstanding projections 16 having sloping or converging surfaces 17 defining reduced edges 18 shaped to conform to the seat 12.

In practical operation, the rod 14 is 50 rotated from the position of Figure 1 to the position of Figure 3 so that the projections 16 are in line with the extension 10 of the opening 9 in the head 8. The rod 14 then can be slid endwise for adjustment. 55 Assuming that the rod is in the position of Figure 3, the rod is rotated, and one of the sloping surfaces 17 of the rod rides along one of the inclined surfaces 11, the projection ultimately being lodged in one of the 60 seats 12. Owing to the duplication of the inclined surfaces 11, of the seats 12, and of the surfaces 17 of the projection 16 of the operating member 14, the said member will 65 be held in place regardless of whether the force exerted on the member 14 is exerted to the right or to the left in Figure 1, it being possible to engage the projection 16 in either of the seats 12 shown in Figure 4.

I claim:—

1. A device of the class described, comprising a support having an opening provided with an extension, an operating rod slidable and rotatable in the opening and having a lateral projection adapted to pass 70 through the extension, the support having a seat wherein the projection is adapted to be lodged, the support having an inclined surface over which the projection rides when the operating rod is rotated to engage the 75 projection in the seat.

2. In a device of the class described, a support having an opening provided with an extension, an operating rod slidable and rotatable in the opening and having a 80 lateral projection adapted to pass through the extension, the support having seats which are duplicated at opposite sides of the support, the support having converging inclined surfaces over either of which the projection rides when the rod is rotated to engage the projection in either seat.

In testimony that I claim the foregoing as my own, I have hereto affixed my signature.

MAURICE R. HORRELL.
